UNITED STATES PATENT OFFICE.

WALLINGFORD C. DEMILT, OF BROOKLYN, NEW YORK.

REPLACEABLE VALVE-SEAT FOR FLUSH-TANKS.

1,222,081.

Specification of Letters Patent. Patented Apr. 10, 1917.

Application filed March 15, 1916. Serial No. 84,319.

To all whom it may concern:

Be it known that I, WALLINGFORD C. DEMILT, a citizen of the United States, residing in Brooklyn, in the county of Kings and State of New York, have invented certain new and useful Improvements in Replaceable Valve-Seats for Flush-Tanks, of which the following is a specification.

The object of my invention is to provide a removable valve-seat, especially but not necessarily or solely limited to use in flush-tank outlet-valves, adapted to be placed as a renewal seat on worn out flush valve-seat thimbles now in use, in a few moments, without breaking the pipe-connection, and which may by the hand, or by the use of a small wrench, or pair of pliers, be easily put into such operative position, and as quickly removed for the purpose of redressing or renewing.

In all flush-tank outlet-valves, especially in those wherein the moving-member is provided with a rubber-seating which abuts against a metallic valve-seat, in the course of a comparatively short time, through corrosion and the electrolytic action, the joint between them becomes more or less broken, and there is consequently a constant leakage. The positioning of the flush-tank is almost invariably such that it is troublesome to redress the valve-seat, or to remove and renew the same; mainly for the reason that the tanks are so small and so situated, and frequently in darkness, that the wrenches or other large sized tools necessary, can be used only awkwardly. The valve-seats on such tank siphon-valves at present in use, are formed integral with and on the annular top of the outlet pipe-thimble which is screwed into the bottom of the tank and connected below with the outlet-pipe. Consequently the thimble being in such a position that it is almost impossible to redress the seating-face, while in position, in order to redress the valve-seat it is necessary to disconnect the outlet-pipe, take out the thimble, redress the valve-seat, and reinsert; or to place in position a new combined thimble and valve seat; all of which is an awkward and comparatively expensive operation.

My said invention is fully shown, described and claimed in the following specification, of which the accompanying drawing forms a part, wherein similar numerals of reference designate like or equivalent

parts throughout the several views, and in which:—

Figure 1 is a view in central longitudinal section of my improved removable valve-seat in position on the outlet-pipe thimble 60 of the flush tank, with the siphoning moving member of the valve in position thereon.

Fig. 2 is a detail top view of my improved removable valve-seat.

Fig. 3 is a side detail view in perspective 65 of such removable valve-seat; and Fig. 4 is a perspective view of a combined pipe-thimble of well known form in position on the floor of the tank, to which such removable valve-seat may be attached as a renewal. 70

Referring to the drawing:—

The outlet-pipe-thimble shown has the upper surface of the top annular securing flange 1 flat or substantially so, and has extending upwardly therefrom the top-flange 75 2, forming as now used also its integral valve-seat, upon which the removable valve-seat 3 fits securely, the abutting faces of 2 and 3 being preferably machined to a water tight joint. The reference numeral 4 designates such pipe-thimble, secured in the floor 5, of the tank by the screw threaded washer-nut 6, a gasket or gaskets 7, being interposed between the top flange 1 and the floor of the tank, to make the joint water tight; 80 and to the bottom of the thimble an outlet-pipe 8 is secured by a union screw joint 9, of the well known form.

My improved removable valve-seat 3 is usually and preferably of the shape and contour shown, comprising the rounded edged annular valve-seat face 10, the annular outer groove 11 (for sake of lightness) and the bottom flange 12, provided on the under annular surface with the gasket grooves 13, 95 between which surface and the upper face 2 of the annular top-flange 1 of the thimble, is interposed a gasket or gaskets 14 of any suitable compressible material, such as leather, rubber, etc., or annularly corrugated 100 lead, copper, etc., to make the joint water tight; and the valve-seat 3 is also provided with the central female screw thread to receive the central siphon starting outlet pipe 16, whereby upon renewal of the valve-seat 105 it is not necessary to renew such pipe 16.

The central orifice of the valve-seat ring 15 is provided with a screw-thread to receive the threaded lower end of the siphon starting outlet standard pipe 16, up and 110

down over which reciprocates the moving siphoning member, comprising the inner pipe 17, upon which is concentrically supported the outer pipe 18, open at the bottom, and in free communication at the top with the pipe 17. Mounted upon the pipe 17 is the soft compressible valve-closing ring and gasket or washer 20, usually of soft rubber fitting on the valve-seat 3; above which, to bring about quick closing action of the valve, is usually secured a heavy weight ring 21, of lead or other suitable material.

To start the siphon upon the raising of the valve closing ring or washer 20, upon the upward movement of the siphon composed of the pipes 18 and 17 and such washer, the water from the tank passes over the annular top of the valve-seat, and into the pipe 16 by way of a plurality of slits or orifices 16' in the wall thereof, which extend from a little below the top of the valve-seat 10, up to about substantially the top of the weight 21, as clearly indicated by dotted lines in Fig. 1; and the water passing therethrough forms a liquid plunger in the pipe 8; and upon the dropping of the valve washer into the closed position shown in Fig. 1, the water in the tank is by the siphonic action thus brought about, drawn up between the inner face of the peripheral wall of the pipe 18, into the top of 17, and thence via pipe 16 into the pipe 8, and thus all the water in the tank is siphoned out, in the well-known manner until the siphon is broken at the bottom of the pipe 18.

While not limiting myself to such securing means, a good and efficient one for removably securing the valve seat to the thimble, I have found to consist of three set-screws 22 passing through the base portion of such valve-seat, so as to contact with the upper flange 2, which screws are equilaterally arranged around the periphery of the valve-seat; and such set-screws may be of any desired form of point or head, but I prefer them to have the heads of the wing

thumb-nut form shown at 23, so that the same can be loosened and tightened by hand without the use of tools. While such set-screws may pass through the peripheral base of the valve-seat at any angle, in order to facilitate the operation of securing and removal of the valve-seat, the same are usually inclined downward as shown to facilitate grasping by the fingers; and in placing in position, the gasket 14 is put in place upon the flange 1 of the thimble 4; the valve-seat is then placed in position and pressed firmly down so as to compress the washer 14 so as to make a water tight joint between the seat and thimble, and the set-screws forced inward to firmly hold the seat in place.

I claim:

1. A removable annular valve-seat provided with a set-screw or screws for securing the same upon an annular thimble or member; such valve-seat being provided with a central female screw thread and having annular gasket grooves in the base. 70

2. A removable annular valve-seat provided with three equilaterally located set-screws passing through the peripheral wall for securing the same in position upon an annular thimble or member; such valve-seat being provided with a central female screw thread, and having annular gasket grooves in the base. 75

3. A removable annular valve-seat provided with three equilaterally located set-screws passing through the peripheral wall for securing the same in position upon an annular thimble or member; such valve-seat being provided with a central female screw thread; having annular gasket grooves in the base; also having an outer central annular peripheral groove; and an annular valve-seat-face of rounded contour in cross-section. 80
